UNITED STATES PATENT OFFICE.

HENRY L. ANDERSON, OF ROCKFORD, ILLINOIS.

DESIGN FOR A COMBINED PLAYING-CARD HOLDER AND SCORE CARD.

Application filed November 4, 1926. Serial No. 19,606. Term of patent 14 years.

To all whom it may concern:

Be it known that I, HENRY L. ANDERSON, a citizen of the United States, residing at Rockford, in the county of Winnebago and State of Illinois, have invented a new, original, and ornamental Design for a Combined Playing-Card Holder and Score Card, of which the following is a specification, reference being had to the accompanying drawing, forming part hereof.

Figures 1 and 2 are views of opposite sides of a combined playing card holder and score card showing my new design. Fig. 3 is an edge view thereof.

I claim:

The ornamental design for a combined playing card holder and score card, substantially as shown.

HENRY L. ANDERSON.
